CHICK BOX

Louis A. Shoemaker, Carleton, Mich., and Andrew E. Miller, Terre Haute, Ind.; said Miller assignor to said Shoemaker.

Application June 8, 1936, Serial No. 84,052

18 Claims. (Cl. 229—35)

This invention relates to boxes for shipping or transporting baby chicks, or other live creatures, so that ventilation and other requirements are necessary.

Generally stated, the object of the invention is to provide a novel and improved construction and arrangement whereby a box of this character is stronger, more rigid, and less liable to accidentally open or come apart, than heretofore, while at the same time the construction is such that the box is economical to manufacture, and in a general way more satisfactory in use than boxes heretofore employed for this purpose.

It is also an object to provide certain details and features of construction tending to increase the general efficiency and desirability of a box of this particular character.

To the foregoing and other useful ends, the invention consists in matters hereinafter set forth and claimed and shown in the accompanying drawings, in which—

Fig. 1 is a perspective of a box embodying the principles of the invention, showing one section of the cover open.

Fig. 2 is a longitudinal section on line 2—2 in Fig. 1, on a larger scale, showing the said cover section in closed position.

Fig. 3 is an enlarged detail fragmentary perspective view of a portion of said box.

Fig. 4 is a similar view of another portion of said box.

Fig. 5 is an enlarged fragmentary section on line 5—5 in Fig. 1 of the drawings.

Fig. 6 is a side elevation of the upper edge portion of one side of the box.

Fig. 7 is a vertical section on line 7—7 in Fig. 6 of the drawings.

Fig. 8 is a plan view of the blank from which the body of the box is made.

Fig. 9 is a similar view of the blank from which the cover sections of the box are made.

Fig. 10 is a side view of a partition for the box.

As thus illustrated, and referring to Fig. 8 of the drawings, the blank, which forms the body of the box, comprises a rectangular bottom section 1, having slots 2 therein, adjacent the transverse fold lines 3 of the blank. The end wall sections 4 have longitudinal slots 5 at the middle thereof, and the raised top wall sections 6 are separated from the said end wall sections by the fold lines 1, as shown, and each section 6 is preferably provided with a middle notch 8, as shown. The ends of the sections 6 are provided with flaps 9, having their inner edges formed with projections 10, as shown. The side wall sections 11 are

connected with the bottom wall section 1 by fold lines 12, and the ends of these side wall sections 11 are provided with flaps 13, the latter having inner edge portions 14 for insertion in the slots 2 when the blank is folded. The side wall sections 11 have wide notches 15 in their outer edges, which are uppermost when the blank is in folded condition. It will also be seen that the blank has the slots 16 formed therein at the four corners of the bottom section 1, through which slots the projections 10 extend when the blank is in folded condition. In addition, the side wall sections 11 have inwardly pressed tabs 17, for assisting in holding the flaps 9 in proper position, when the blank is folded, and also have slots 18 for a purpose that will hereinafter more fully appear.

The cover construction comprises a blank, as shown in Fig. 9 of the drawings, having upright middle wall sections 19, formed at their ends with projections 20 and with ventilating slots 21, parallel with the fold lines 22 and 23. The slot 24 is preferably formed to cross the fold line 23 at right angles thereto, substantially midway between the outer ends of the sections 19 of the cover construction. The top wall sections 25 are hinged at the fold lines 22, have their ends formed with tabs 26 that can be bent down outside the box, at the sides thereof, and these sections 25 have end flaps 27 that are bent up when the two cover sections 25 are in closed position.

A third blank or section is employed, as shown in Fig. 10, comprising a longitudinal divider wall 28, formed at ends with projections 29 to engage the slots 5, and at its upper edge with a wide notch 30, having vertical end edges 31, and a middle notch 32, which latter receives the portions of the cover section at the ends of the slot 24, when the structure is assembled.

The blanks are folded and assembled as shown in Figs. 1, 2, 3, 4, 5, 6 and 7 of the drawings. Preferably, the cover wall sections 25 are provided with tabs 33 that can be bent down outside of the side wall section 11, as shown, to retain these side wall sections against outward displacement at their upper edges. The tabs 26 can be bent down, to in effect produce notches to receive a binding wire or cord 34, as shown in Fig. 5 of the drawings, thus providing for a tie wire or cord in a manner that will not cause the same to cut into the upper edges of the box, as these wires or cords will rest on the tabs 26, as shown in the drawings. In this way, the sections 19 and 28 serve to divide the interior of the box into four rectangular compartments, one at each corner of the box. The portions 10 are very effective to

keep the corner construction of the box in locked condition, so that it cannot get loose, and so that the chicks cannot be injured by getting in between loosened portions. When the cover sections are closed, it will be seen that the notches 8 are immediately above the upper edges of the end portions of the section 28, so that the edges 31 hold the upper edges of the flap sections 27 quite close to the inner edges of the sections 6, 10 at the middle of the latter, while between these notches 8 and the sides of the box, the upper edges of the sections 27 may spring inwardly enough to insure a locking engagement with the under sides of the sections 6 when the latter are 15 in folded position, as shown in Figs. 1 and 2 of the drawings. In this way, two fingers may be inserted through the notches 8, one at each side of the divider section 28, to pull the middle portion of each flap section 27 outwardly, thereby 20 to release these flaps 27 from under the overhanging sections 6, so that the cover section 25 may then be swung upwardly into open position, as indicated in Fig. 1 of the drawings. In this way, only one hand, and one engagement thereof 25 with the section 27, is necessary in opening the covers. The projections 14, which enter the slots 2, when the blanks are folded and assembled, are very effective to hold the corner construction in firm and locked condition.

30 Obviously, any or all of said walls can be perforated, or provided with holes, to provide circulation for the baby chicks, or other live creatures.

In effect, the portions 10 are cut out of the flaps 13, and the portions 14 are cut out of the 35 ends of the walls 4 of the blank, as shown in Fig. 8 of the drawings.

It will be observed that the flap portions 9 which are bent down from the top wall sections 6, and which are provided with the projections 10 40 that extend outwardly at the corners of the box, serve as interlocking means for holding the 45 projections 14 in the slots 2, so that the corner construction is very strong and effective, as none of the projections are likely to slip or pull out of their respective or allotted slots, when the box is filled and shipped, or even when it is handled roughly.

What we claim as our invention is:

1. In a baby chick box, or box for similar 50 purposes, a blank comprising a bottom section provided with foldable end and side wall sections, all interlocked in box form, the bottom section having slots, and the side wall sections having end flaps in the vertical planes of said slots and 55 provided with projections for engaging said slots when the blank is folded, with said end flaps inside of said end wall sections, and held flatwise against the inner surface of the latter by the downward insertion of said projections in said 60 slots, said blank having interengaging locking means having portions that extend outside at the four corners of the box, serving to hold said 65 projections in said slots.

2. In a baby chick box, or box for similar 70 purposes, a blank comprising a bottom section provided with foldable end and side wall sections, the end wall sections having foldable flaps along the upper edges thereof, each flap having a foldable portion at each end thereof, each foldable portion having a projection on its inner edge at 75 its outer end thereof, and each box corner, when the blank is folded, having a slot to receive the projection of one of said foldable portions, when the latter are folded to extend downwardly inside of the end and side wall sections.

3. A structure as specified in claim 2, comprising slots in said bottom wall section, foldable flaps for the ends of the side wall sections, and projections on said last-mentioned flaps for engaging said last-mentioned slots in the bottom section, cooperating with said first-mentioned projections to form a tight and rigid locking construction for each corner of the box. 5

4. A box that can be opened and closed, made of flexible sheet material, comprising a blank 10 formed to provide the rectangular body of the box, with a bottom and four upright side walls, and with the exterior of said body exposed when the box is closed, two opposite side walls having substantially rectangular end flap sections bent at 15 right angles to these two side walls to extend toward each other inside the box and form reinforcing portions of the other two side walls, so that the latter cover the entire outer flat surface of said reinforcing portions, said blank having sections that form portions of the top wall of the box, at opposite sides of the latter, and means inserted down from the top of the box and then out at the corners of the box for holding said top wall portions in exposed position against upward displacement. 20

5. A structure as specified in claim 4, said flap sections having interlocking engagement with said holding means and having horizontal upper and lower edges disposed substantially in the 30 planes of the upper and lower edges of said other side walls.

6. A structure as specified in claim 4, comprising provisions in the bottom of the box for holding said flap sections snugly against the inner 35 surface of said other side walls.

7. A structure as specified in claim 4, comprising means for retaining said holding means in interlocking engagement with said other side walls. 40

8. A structure as specified in claim 4, comprising slots in the bottom of the box to engage and hold said flaps in position.

9. A structure as specified in claim 4, a portion of said holding means being cut out of 45 corners of said flaps.

10. A box of the type described, comprising a box body formed from a single foldable blank with a rectangular bottom and four side walls, two opposite side walls having end flaps formed 50 at their lower edges with engaging portions, said bottom wall having slots at the lower edges of the other two side walls, to receive said engaging portions and hold the latter snugly against the inner surface of said last-mentioned side walls, and 55 means including integral flaps extending downward inside the box to retain said last-mentioned side walls in upright position.

11. A structure as specified in claim 10, said retaining flaps having interlocking engagement 60 with said other side walls.

12. A structure as specified in claim 10, said retaining flaps having interlocking engagement with said other side walls, and with edges of said flaps. 65

13. A structure as specified in claim 10, said engaging portions being cut out of the ends of said other walls, and said inside flaps being integral with the ends of top wall sections of the blank. 70

14. A box of the type described, comprising a box body formed from a single foldable blank with a rectangular bottom and four side walls, all interlocked in box form, two opposite side walls having end flaps formed at their lower 75

edges with engaging portions, said bottom wall having slots to receive said engaging portions, to hold the latter snugly against the inner surface of the other two opposite side walls, and means 5 to retain the latter walls in upright position, forming said interlock, said retaining means having engagement with all of said side walls, serving to keep said engaging portions in said slots.

15. A box of the type described, comprising a 10 box body formed from a single foldable blank with a rectangular bottom and four side walls, all interlocked in box form, two opposite side walls having end flaps formed at their lower edges with engaging portions, said bottom wall having 15 slots to receive said engaging portions, to hold the latter snugly against the inner surface of the other two opposite side walls, and means to retain the latter walls in upright position, forming said interlock, said retaining means having engagement with all of said side walls, and with vertical edges of said flaps, serving to keep said 20 engaging portions in said slots.

16. A carton formed from a blank of flexible material cut and scored to provide a bottom and four side walls hingedly connected to the bottom, one pair of opposite side walls having integral corner flaps at opposite ends thereof lying against the inner surfaces of the other side walls, said corner flaps having downwardly extending projections inserted through slots provided at the juncture of the second named side walls and the bottom, and locking means having portions projecting outward at the corners of the carton, holding said projections in said slots. 5

17. A structure as specified in claim 16, said projecting portions being integral with top wall sections of said blank. 10

18. A structure as specified in claim 16, said projecting portions extending through slots in said flaps in vertical planes at right angles to the vertical planes of said first mentioned slots. 15
